COMB

Louis Levin, Chicago, Ill., assignor to Charles Levin & Co., Chicago, Ill., a corporation of Illinois

Application May 14, 1957, Serial No. 659,128

4 Claims. (Cl. 30—200)

This invention relates to attachments for hair clippers and the like, and more particularly to comb-type attachments intended to be secured to the cutter head of a hair-clipper, to facilitate the hair cutting operation.

An object of the invention is to provide a novel and improved, comb-type guide attachment for a hair clipper, which will particularly facilitate the cutting of the hair above and around the ears, and also at the rear of the head generally in a zone level with the ears.

Another object of the invention is to provide a novel and improved comb-type guide attachment as above set forth, which is reversible as regards applying it to the head, so that it may be used with equal facility at either the right or left side of the head.

Still another object of the invention is to provide a novel and improved attachment for a hair-clipper, by which the hair may be cut so as to have at one place appreciable length and at another place a relatively short length, both for left side and right side use, this being effected by different portions of the cutter head, thereby to easily obtain a feathering of the hair and a desirable blending thereof at either side of the head about and above the ears.

A feature of the invention resides in the provision of a novel and improved comb-type guide attachment for the cutter head of a hair clipper, wherein comb teeth are so provided as to define oppositely-directed angles or slopes from a center or medium line, and to define by their free edges a pointed front, thereby to enable left and right angular or taper cuts to be readily effected.

Another feature of the invention resides in the provision of a novel and improved guide attachment as above characterized and having all of the stated features and advantages, which is nevertheless simple in its construction and economical to fabricate and assemble or attach.

Other features and advantages will hereinafter appear.

In the drawings accompanying this specification, similar characters of reference are used in the various figures wherever possible.

Figure 1 is a side elevational view of an improved comb-type guide attachment for a hair-clipper, made in accordance with the invention.

Fig. 2 is a plan view of the under side of the attachment shown in Fig. 1, such under side being that intended to engage the hair or head of the person having the hair cut.

Fig. 3 is a front edge elevational view of the attachment shown in Figs. 1 and 2.

Fig. 4 is a transverse sectional view taken on the line 4—4 of Fig. 1.

Referring now particularly to the figures, there is shown in Fig. 1, in broken outline, a usual type of hair clipper having a casing 10 and a cutter head 11, the latter being provided with a reciprocable cutter blade 12 and a stationary cutter blade 13.

By the present invention I provide a novel and improved comb-type guide attachment for the cutter head

2

11, comprising a base member 15 adapted to be applied to the stationary cutter blade 13, to underlie the same. The base member 15 may have any usual type of attaching means, that shown herein by way of example being a U-shaped metal spring clip 16 having a yoke portion 17 secured to the base 15 by rivets 18 or the like. The spring clip 16 may have a pair of opposed fingers 20 adapted to engage and embrace the side edges of the stationary cutter blade 13, thereby to rigidly mount the base member 15 on such blade. Further support of the base 15 on the blade 13 is also provided, as will be hereinafter brought out in detail.

On the base member 15 I provide a plurality of elongate, substantially parallel, deep and narrow comb teeth numbered 22 through 28 respectively, such teeth extending in one general direction from the base, shown as downward and to the left as viewed in Fig. 1.

The comb teeth 22-28 are disposed in a row extending transversely of the stationary cutter blade 13, and are graduated in lengths with the center teeth being longer and the teeth at the two ends of the row being shorter. Thus, as viewed in Fig. 2, the free ends of the teeth 22-28 (at the left) will lie in a bowed or broken line. It will be seen that the free end of the center tooth 25 and the free ends of the three teeth 22, 23, 24 at one side of the center tooth define actually a straight line, and the same is true of the center tooth and the teeth 26, 27, and 28 at the other side of the center.

All of the teeth 22-28 taper to relatively sharp points 30 at their free ends, as clearly seen in Fig. 1. Also, the teeth have one set of edges, indicated at 30 in Fig. 1, disposed substantially in a common flat plane. The opposite set of edges of the teeth define a bulged surface, as may be seen in Figs. 3 and 4. Considering these latter figures, it will be noted that corresponding edges of the center tooth 25 and the teeth 22, 23, 24 lie in a common flat plane, whereas the corresponding edges of the center tooth 25 and the teeth 26, 27, 28 lie in a different common flat plane, both of said planes being angularly disposed with respect to each other and intersecting along the edge of the tooth 25.

As seen in Fig. 1, the opposite working edges of each of the teeth 22-28 are straight and angularly disposed with respect to each other, meeting at the free ends or tips of the teeth. Also, the corresponding edges 30 of the teeth which are disposed in the common flat plane are much shorter than their opposite edges, indicated at 32, 33, 34, 35, 36, 37 and 38 in Figs. 1 and 4.

The comb teeth 22-28 have shank portions which are not as deep as the tapered portions, such shank portions being seen in Fig. 1 and having parallel upper and lower edges. Adjacent the edges of the shank portions I provide shoulders 40 on the teeth, such shoulders being disposed in a straight line extending across the front cutting edge of the cutter head 11. The shoulders 40 are intended to engage the tips of the teeth of the stationary cutter blade 13, and to thereby position the attachment on such cutter blade. Also, the sloping face indicated at 42, of the stationary cutter blade 13 is engaged by the edges of the shank portions of the teeth 22-28, thereby to further effect a positioning of the attachment on the cutter head.

While the present improved attachment may be fabricated in any suitable manner and of any suitable material, I prefer to mold it of a plastic composition such as nylon or the like. Nylon is the generic name for all materials defined as synthetic fiber-forming polymeric amides. Thus, the attachment will be at one and the same time strong and light in weight. Also, it may be readily cleaned, and the sanitary aspect is one of importance also. By forming the attachment mainly of molded nylon the teeth will have appreciable strength, and will not warp or lose their shape readily.

The attachment finds particular use in cutting the hair at both sides of the head, around and above the ears and in a zone at the rear of the head, approximately on the same level as the ears. The natural outline of a hair cut may be followed, with one half or the other half of the attachment being utilized to obtain a tapering and blending effect. That is, either the center tooth 25 and the three teeth 22-24, or the center tooth 25 and the three teeth 26-28 are made to rest on the head, and the clipper advanced to shear the hair picked up by the teeth. It will be observed that the improved attachment of this invention is thus adaptable for both left hand and right hand use, and that one side portion or the other may be utilized as required, in trimming the hair to the desired outline at one side or the other of the head. The center portion of the attachment will of course trim the hair to have a greater length, whereas either side portion of the attachment will cut the hair to a much shorter length. Therefore a proper tapering and blending effect may be easily obtained. The clipper may be advanced from one side of the head to the other, back and forth above the neckline, to blend the hair well without ridges. With the improved attachment as above set forth the taper at the sides of the head may be readily blended with the taper at the back of the head, thereby to effect an attractive hair cut.

I attribute the advantages of my improved attachment to the disposition of the free ends of the teeth in a bowed or broken line, together with the tapering of the teeth and the disposition of the long edges 32-38 so as to define a bulged surface, or a pair of planar surfaces disposed angularly and intersecting each other at the center tooth 25.

Variations and modifications may be made within the scope of the claims, and portions of the improvements may be used without others.

I claim:

1. A comb-type guide attachment for a hair clipper,

comprising a base member having a generally flat, expansive surface and means for attaching it to a flat-surfaced cutter head with the said expansive surface engaged with the flat surface of the cutter head; and a plurality of 5 elongate, substantially parallel deep and narrow comb teeth carried by said base member and extending in one general direction therefrom, said teeth being disposed in a row and being of graduated lengths with the center teeth longer and the teeth at the two ends of the row shorter 10 whereby the free edges of the teeth lie in a bowed or broken line, said teeth tapering to relatively sharp points at their free ends, having one set of edges relatively short and disposed substantially in a common flat plane, and having relatively long, straight opposite edges extending 15 at similar, acute angles of appreciable magnitude to the said expansive surface and disposed so as to define a bulged surface.

2. The invention as defined in claim 1 in which the opposite edges of each tooth are straight and meet at the 20 free end of the tooth in an acute angle, the opposite edges of all those teeth disposed at a side of the center-most tooth of the attachment being all of different lengths.

3. The invention as defined in claim 2 in which the 25 said long, straight edges are disposed in two, angularly-disposed, intersecting planes.

4. The invention as defined in claim 1 in which the edges of the said one set are shorter than those of the 30 said other set, and in which the teeth have shank portions of reduced depth, and have shoulders disposed at said shank portions and in a straight line.
